UNITED STATES PATENT OFFICE.

EDWIN J. CONNOR AND ARTHUR R. RALSTON, OF OMAHA, NEBRASKA.

LIFTING TONGS.

Application filed April 12, 1922. Serial No. 551,863.

To all whom it may concern:

Be it known that we, EDWIN J. CONNOR and ARTHUR R. RALSTON, citizens of the United States, residing at Omaha, in the 5 county of Douglas and State of Nebraska, have invented certain new and useful Improvements in Lifting Tongs, of which the following is a specification.

Our invention relates to hoisting tongs 10 and has special reference to tongs for engaging heavy rails and supporting them while they are being moved from point to point in loading or unloading, although the device is capable of use upon other heavy objects. 15 One object of the invention is to provide hoisting tongs which may be automatically engaged with the head of a rail and easily released therefrom after the rail has been brought to the point of delivery. A further object of the invention is to provide 20 means whereby the rail-engaging members may be locked against release and held in locked position while the rail is being shifted, and a further object of the invention is 25 to provide simple and efficient means whereby the rail-engaging members may be easily engaged with the rails and held thereto prior to the lifting action, and a further object is to provide means whereby such 30 locking means will be automatically released to permit discharge of the rail or other load. Other incidental objects of the invention will appear in the course of the following description.

35 In the annexed drawings, which illustrate one embodiment of our invention,—

Figure 1 is a perspective view of hoisting tongs embodying our improvements;

Fig. 2 is an elevation with one side plate 40 and one load-engaging jaw removed, the device being shown in the position prior to complete engagement of the load by the jaws;

Fig. 3 is a view with one side plate removed and parts in section showing the jaws engaged under the head of a rail;

Fig. 4 is an enlarged view similar to Fig. 3 but showing the rail fully engaged and all the parts in the position assumed when the 50 rail is being shifted;

Fig. 5 is a detail section on the line 5—5 of Fig. 4;

Fig. 6 is a detail perspective view of the plunger or locking member;

55 Fig. 7 is an enlarged detail perspective view of one of the load-engaging jaws.

In carrying out our invention, we employ side plates 1 which may be held in spaced relation by spacer blocks 2 and 3 interposed between them at their upper ends and at 60 intermediate points, and these spacer blocks may be separate elements or may be formed integral with one of the face plates. The upper ends of the plates are connected by a cap plate 4 which is constructed with a transverse slot 5 through which the end of the latch 6 projects. The side or face plates 1 are suitably shaped on their inner faces to provide a recess or chamber 7 and a shoulder or lug 8, the purposes of which will 70 presently appear, and the latch 6 is disposed between the spacer blocks 2, as shown most clearly in Fig. 4. The plates 1 are provided upon their edges above their centers with lateral extensions or lugs 9 and are properly shaped at their lower ends to provide depending tongues or lugs 10 at their corners. A plunger or locking head 11 is slidably fitted between the plates 1 and the spacer blocks 3 and is guided in a rectilinear 80 path by the surfaces of the face plates and the said spacer blocks, as will be readily understood upon reference to the drawings. This locking head is provided with a suspension pin or eye 12 at its upper end, and a spring 13 is attached at its lower end to the said suspension member, and at its upper end to the cap plate 4, the strength of the spring being constantly exerted to hold the locking head in a raised position. The latch 90

6 is pivoted at its lower end to one side of the locking head, and is provided upon one side edge with a tooth 14 adapted to engage the upper side of the cap plate 4 and thereby support the plunger head in a raised position, and upon its opposite edge the latch is provided with a tooth or shoulder 15 adapted to engage the shoulder 8 provided on one of the side plates 1. When the shoulder 15 engages the shoulder 8, the latch and the locking head will be prevented from moving upwardly and will, therefore, retain the working parts in the load-engaging position until the latch or operating handle member 6 is manually shifted to release the shoulder 15. In the lower end of the locking head is a transverse groove or recess 16 which is adapted to receive the tongues 17 projecting from the load-engaging members near the upper ends of the same. These tongues 17, 110 when the two load-engaging members are in locked position, will overlap so as to fill the

recess or groove 16, as shown most clearly in Fig. 4; and the locking head will pass between the flat vertical surfaces 18 of the load-engaging jaws so that movement of these jaws will be positively prevented. The load-engaging members or jaws comprise a vertical intermediate or shank portion 19 which is pivotally mounted between the lower portions of the tongues 10 of the face plates, and the pivots 20 for these load-engaging members may also be utilized as the bolts by which the face plates are held together. The outer surface of the shank 19 at the upper extremity thereof is curved, as shown at 21, whereby it may readily clear the adjacent spacer block 3 when the member swings pivotally. Each tongue 17 projects from a lower corner of the flat face 18, and upon one load-engaging member the tongue is arranged at the front side, while upon the other load-engaging member it is arranged at the rear side so that the tongues may overlap when a load is held. From the lower end of the shank 19, a sustaining jaw 22 projects inwardly in approximately parallel relation to the respective tongue 17, but this jaw 22 is expanded so that it is appreciably wider than the shank and will therefore, have sufficient strength to sustain the load with which it is engaged. To limit the pivotal movement of the load-engaging jaws or members, we provide studs or stop pins 23 which play in arcuate grooves or slots 24 in the face plates 1 so that by the engagement of the said studs or pins with the ends of the slots or grooves the movement of the load-engaging members will be limited. We thus prevent the said members assuming a position in which they can not be easily brought into proper relation to the load and also aid the locking head in preventing excessive movement of the load-engaging members in the opposite direction.

Pivots supported between the lugs or ears 9 by the bolts 25, which are passed through said lugs and serve also to fasten the face plates together, are angle levers 26 which have their shorter arms 27 arranged to bear upon the upper end of the locking head 11 and have their longer arms extended upwardly and outwardly from between the lugs 9. In the upper extremities of the longer arms of these angle levers are engaged chains 28 which are connected at their inner ends by a ring or link 29 which, in turn, is engaged by a suspending hook 30. The suspending hook 30 is, of course, carried by the lower end of a power cable which depends from a crane or other load-sustaining and moving instrumentality. It will be readily noted upon reference to the drawings that the shorter arms 27 of the angle levers terminate in convex surfaces constituting toes which may rock easily upon the upper end of the locking head. It will also be noted

that a coiled spring 31 is arranged above the recess or chamber 7 of one side plate 1 and is secured at its opposite ends to the latch 6 and the base of the said recess respectively.

The construction and arrangement of the several parts of our device being thus made known, it is thought the operation of the same will be readily understood. When a rail, for instance, is to be lifted by the use of our device, the latch or controlling handle member 6 is shifted manually so that the tooth 15 will be released from the shoulder 8, whereupon the spring 13 will contract and draw the member 6 upwardly through the slot 5 in the cap plate, while at the same time the spring 31 will be placed under tension and will draw the shoulder or tooth 14 into position over the cap plate at the end of the slot 5 so that the latch and the locking head will be supported in the raised position and prevented from moving downwardly even though the spring 13 should be broken. When the locking head is thus raised, the lifting arms or levers 26 will, of course, be moved apart at their upper ends, as shown in Fig. 2, and the load-engaging members may assume the position shown in said Fig. 2 with the tongues 17 in a partly depending position and the sustaining jaws 22 swung laterally outward. The engagement of the tooth 14 with the cap plate 4 will prevent the levers 26 swinging about their pivots inasmuch as the extremities of their lower arms are in constant engagement with the upper end of the locking head and, as the locking head is raised and held in its uppermost position, movement of the levers will be prevented. The operating cable may, therefore, be released so that the tongs may descend over the rail to be shifted, this movement bringing the tongues 17 into contact with the head of the rail, as will be readily understood upon reference to Fig. 2. The continued downward movement of the device will, of course, then cause the load-engaging members to swing about their respective pivots and assume the position shown in Fig. 3 with the load-sustaining jaws 22 engaged under the head of the rail. The tooth 14 is then released from the cap plate 4 by exerting a lateral and downward pressure manually upon the upper end of the latch 6 so that the locking head will be depressed until the tooth 15 engages under the shoulder 8. This downward movement of the locking head will cause the grooved or recessed lower end thereof to pass over the tongues 17 and bring the sides of the body portion of the locking head slightly between and in engagement with the flat vertical faces 18, as shown in Fig. 3. Pivotal movement of the load-engaging members will thus be prevented and consequently they cannot be accidentally or pre-

maturely released from the rail. If, now, the power be applied to the operating cable so as to pull upwardly upon the same, the chains 28 will be caused to move toward 5 vertical positions and thereby swing the levers 26 upon their fulcrums, as will be readily understood upon reference to Figs. 3 and 4, and cause the toes or lower ends of these levers to press downwardly upon 10 the locking head so that a further downward movement is imparted to the same and the lower extremity thereof will be caused to bear upon the top of the rail head, thereby firmly gripping the rail between 15 the said locking head and the jaws 22, as shown clearly in Fig. 4. Of course, the downward movement of the locking head will release the tooth 15 from the shoulder 8 and the spring 31 will then at once move 20 the latch so that straight upward movement of the same will cause the tooth 15 to clear the said shoulder 8. The weight of 25 the rail or other load to be moved, together with the entire weight of the tongs, is carried by the operating cable so that the upper ends of the levers 26 tend constantly to swing together and a very powerful force is applied to the upper end of the locking head to hold the same against the load. 30 In this position, the entire face 18 of each load-engaging member will be engaged by the adjacent side or end of the locking head and, consequently, inward swinging movement of the load-engaging members is pre- 35 vented so that release of the load cannot occur until the tension upon the operating cable is removed. Of course, this tension will not be removed as long as the rail or other load is suspended in the device above 40 the ground, but when the load comes in contact with the ground, a loading platform, or the floor of a car, the tension upon the operating cable will be released and if it then be lowered the upper ends of the levers 45 will move apart, permitting the locking head to raise and the load engaging members to be released from the load. When the rail has been deposited upon the ground or other fixed support, the pressure exerted 50 upon the locking head will be released so that the spring 13 may contract and lift the head and carry the latch 6 through the slot 5, whereupon the spring 31 will pull the tooth 14 into engagement with the upper surface of the cap plate. If a lifting pull be then exerted through the operating cable upon the upper ends of the levers 26, the levers will be prevented from swinging about their fulcrums but the entire device 55 will be raised and the engagement of the jaws 22 with the head of the rail will cause them to swing about their pivots and again assume the position indicated in Fig. 2 so that another rail may be engaged and the 60 transferring operation repeated. 65

It will be readily seen that we have provided a very simple, compact and efficient device whereby rails and other heavy objects having projecting portions may be easily and rapidly shifted. The apparatus 70 will be found exceedingly advantageous in unloading railway rails from freight cars onto the ground where the rails are to be laid or upon platforms where they are to be stored. It is to be understood, however, that the apparatus may be employed for handling channel irons, I-beams, and a great variety of other material and heavy 75 objects.

Having thus described the invention, what 80 is claimed as new is:

1. An apparatus for the purpose set forth comprising a pair of opposed coacting load-engaging jaws, a locking head arranged above and adapted to engage between the jaws 85 to lock them to a load, means acting constantly on the head and actuated by a lifting force to move it into engagement with the jaws, and means for withdrawing the head from between the jaws when the lifting force 90 is removed.

2. An apparatus for the purpose set forth comprising a pair of coacting load-engaging jaws, a locking head engageable between the jaws, releasable means for holding the head 95 in engagement with the jaws, means actuated by a lifting force to release said holding means and maintain engagement of the head with the jaws, and means for withdrawing the head when the lifting force is removed. 100

3. An apparatus for the purpose set forth comprising a pair of opposed coacting load-engaging jaws, means for causing the jaws to automatically engage a load, a locking head adapted to engage between the jaws 105 and bear upon the load whereby the jaws will be locked to the load and the load may be suspended, and means acting constantly on the head for binding said locking head against the load and lifting the load, the 110 locking head and the jaws.

4. The combination of a pair of opposed coacting load-engaging jaws, a locking head slidably mounted above the jaws and arranged to enter between them and bear upon 115 the load, angle levers arranged at opposite sides and above the locking head and bearing constantly thereon to force the head between the jaws, and means for applying power to said levers whereby to bind the 120 locking head upon the load and in engagement with the load-engaging jaws.

5. The combination of a pair of opposed coacting load-engaging jaws, a locking head slidably mounted above the jaws and adapted to engage between them, yieldable means tending constantly to lift the locking head from the jaws, means for engaging the locking head between the jaws and holding it in the engaged position, and means whereby 130

when a lifting power is exerted upon the jaws the locking head will be caused to further engage the jaws and to bind upon the load.

6. The combination of a sustaining structure, load-engaging jaws pivotally mounted in the lower ends of the sustaining structure, a locking head slidably fitted within the structure and adapted to engage the load-engaging jaws whereby to prevent release thereof, a latch pivoted to the locking head and extending through the upper end of the sustaining structure, said latch being provided with opposed teeth upon its opposite sides adapted to engage respectively with an internal portion of the sustaining structure or over the upper extremity thereof whereby to maintain the locking head in either a lowered or a raised position, a yieldable connection between the locking head and the top of the sustaining structure, yieldable means acting upon the latch and tending to hold it free of internal engagement with the sustaining structure, and operating levers

mounted within the sustaining structure 25 and connected with a suspending cable and bearing constantly upon the locking head.

7. A device for the purpose set forth comprising a sustaining structure, load-engaging members pivotally mounted within the lower end of the sustaining structure and provided near their upper ends with inwardly projecting tongues adapted to engage upon a weight to be raised whereby downward movement of the sustaining structure will cause the load-engaging members to grip said weight, a locking head slidably mounted within the sustaining structure, means tending constantly to maintain the locking head out of engagement with the load-engaging members, and means for driving the locking head into engagement with the load-engaging members and applying a load-sustaining and lifting force thereto.

In testimony whereof we affix our signatures.

EDWIN J. CONNOR.
